UNITED STATES PATENT OFFICE.

ARTHUR L. STANFORD, OF CHICAGO, ILLINOIS.

RAIL-ANCHOR.

1,196,488.

Specification of Letters Patent. Patented Aug. 29, 1916.

Application filed June 17, 1916. Serial No. 104,229.

To all whom it may concern:

Be it known that I, ARTHUR L. STANFORD, a citizen of the United States, residing at Chicago, county of Cook, and State of Illinois, have invented certain new and useful Improvements in Rail-Anchors, of which the following is a specification.

The object of this invention is to simplify the construction of a rail anchor so as to reduce the cost of production as much as possible without sacrifice of the elements of strength, durability and efficiency in the performance of its intended work.

With these ends in view, the anchor is designed as a two-piece structure so formed and proportioned that both parts can be cast in the foundry and completed without machining, which is an item of expense which it is desirable to avoid, if possible.

Another object of the invention is to so proportion the parts that the bulk of the metal will be disposed at the points subjected to strain, the remaining portions of the device being lightly designed to reduce the expense without sacrifice of strength or durability.

The invention also relates to the construction of the nut which is employed to hold the jaws in operative position and to the provision of nut locking elements which likewise subserve a jaw function in clamping the anchor to the rail flange and to the device as a whole and the features thereof, hereinafter to be described.

In the drawings: Figure 1 is a view showing a rail base in cross-section with the anchor of the present invention applied thereto; Fig. 2 is a side elevation of the same showing the foot of the anchor in contact with a tie; Fig. 3 is a top or plan view of the device; and Fig. 4 is a view of the rear face of the nut element.

The anchor, as before stated, consists of two parts, a rail-gripping element 5 and a locking or nut element 6. The rail-gripping element comprises a jaw 7 consisting of an overhanging portion 8 and a base portion 9 in spaced relation to one another. The under or acting face of the overhanging jaw portion is sloped or beveled to conform to the upper surface of a rail flange, and the receiving space within the jaw is preferably of slightly greater depth than necessary to bring the parts into gripping contact with the rail in order to afford a slight clearance space 9^a at the base of the

jaw to allow for inequalities in the surface contour of the rail flanges, and to eliminate the formation of cleavage cracks.

The jaw as a whole is formed to afford a body portion 10 which merges at its inner and outer ends into transversely projected inner and outer reinforcing flanges 11 and 12 respectively, which flanges serve to greatly thicken the jaw at its inner and outer ends in order to afford the necessary resistance to strain or breakage occasioned by the tendency of the jaw to tilt when subserving its anchoring function.

The inner reinforcing flange 11, at its lower end, merges into a forwardly projected foot 13 adapted to contact with the surface of a tie 14 and preferably slightly rounded on its acting face to compensate for inequalities in the surface of a hewn tie, abutting against that face of the tie which may be considered as the rear face with respect to the direction of traffic on the rails, which is indicated by the arrow in Fig. 2. It will be noted that the formation is one which affords a clearance between the tie and the forward reinforcing flange, so that the device as a whole will subserve the functions of a lever having an arm equal to the distance between the point of tie contact with the foot and the forward jaw contact with the rail. When, therefore, the rail tends to creep, there will be a tendency to tip or rock the jaw upon the foot as an axis, which will cause a very severe binding or gripping of the jaw against the surface of the rail flange, and a like result will follow if the rail tends to draw away in the opposite direction, due to contraction in cold weather, in which case the foot embedded in frozen ballast will tend to rock the jaw in a reverse direction.

The foot is reinforced by means of a rear web 14' which bridges the space between the front reinforcing flange with its projected foot and the rear flange, and this connecting web is positioned to lie immediately behind the center of the foot which moreover is in substantially vertical alignment with the longitudinal center of contact of the upper jaw member with the interposed rail flange. The arrangement is one which affords a very heavy reinforcement for the parts immediately at or near the points subjected to the greatest strain during the operation of the device.

The gripping member heretofore described is provided with an inwardly extend-

ing cross arm 15 which is spread or enlarged at its connecting end 16, where it merges into the lower portion of the jaw member, and the upper surface of the connecting arm 5 is slightly depressed below the upper surface of the lower jaw member in order to afford a clearance space 17 between the arm and the under surface of the gripped rail flange. The arm, throughout the major portion of 10 its length, is comparatively thin in its horizontal, as compared with its vertical dimension, and is provided at or near its center with a bend or curve 18 which is designed to afford a limited amount of flexibility, so 15 that when the parts are driven to place on the rail flange, they will preferably be held under a slight amount of spring tension, thereby compensating for vibration due to traffic on the rails.

20 The outer end of the connecting arm, beyond the bent portion, is provided on its upper and lower edges with screw threads 19, which are designed to receive a nut 20 having a flange or collar 21 preferably provided 25 with cuts or notches 22 at recurrent intervals around its edge, or otherwise irregularly formed. The flanged nut is adapted to thread onto the upper and lower threads 19 and be turned to position in contact with the 30 edges of the rail flanges. Thereafter the nut will be held in locked position against the rail flange by striking down the upstanding portion of the collar so as to overlie the rail flange and subserve the purpose and function 35 of a combined overhanging jaw and nut-lock. The notches also facilitate the turning of the nut by means of a hammer and chisel, spike, or the like, which may be applied to the notched surface and driven around.

40 In use the gripping elements of the device will be driven in place to engage the intended rail flange, after which the nut will be turned to position and struck down by the employment of a hammer, or other convenient implement. The connecting arm at its end is threaded sufficiently to allow for considerable 45 variation in the width of the rail base, and the provision of the curve in the connecting arm enables the nut to be locked in suitable 50 position to hold the device onto a rail so tightly as to withstand the very heavy vibration to which the parts are subjected.

55 The clearance space 9^a at the base of the jaw is preferably slightly enlarged to prevent shrinkage cracks in the casting operation, and also to make possible a driving fit of the jaws onto the rail flanges. The extreme simplicity of the device enables the 60 parts to be cast and used without any milling or machine work, which is an element of much importance in the art to which the present invention relates. The device as a 65 whole is extremely simple and readily adaptable to use with rails of various sizes, and all 70 portions of the device are made sufficiently

strong to withstand the strains encountered. The connecting arm and lock nut are subjected to very little strain in use, and these parts are made correspondingly light. The only service which the nut and arm are required to perform is that of holding the jaw member in gripping contact with the rail and in preventing its displacement, since the gripping or binding action of the jaws under strain is in a plane parallel to the rail, 75 and the connecting arm and nut are not subjected to this load in any appreciable degree. The parts, furthermore, are proportioned so that the notched collar on the nut will clear the edge of the tie, thereby facilitating the turning up of the nut to position. 80

I claim:

1. A rail anchor consisting of a jaw member adapted to grip a rail flange, a transverse connecting member adapted to underlie the rail base, and a locking member mounted on the end of the connecting member and adapted to be positioned thereon to contact the opposite rail flange and provided with an upstanding portion adapted to be struck down onto the rail flange, substantially as described. 85

2. A rail anchor consisting of a jaw member adapted to grip a rail flange, a transverse connecting member adapted to underlie the rail base, and a locking member threaded on the end of the connecting member and adapted to be turned thereon to position to contact the opposite rail flange and provided with an upstanding portion adapted to be struck down onto the rail flange, substantially as described. 95

3. In a rail anchor, the combination of a gripping member adapted to engage a rail flange and provided with a depending foot adapted to abut against the rear vertical face of a tie, a transverse connecting member adapted to underlie the rail base, and a locking member mounted on the end of the connecting member and adapted to be positioned thereon to contact the opposite rail flange and provided with an upstanding portion adapted to be struck down onto the rail flange, substantially as described. 105

4. In a rail anchor, the combination of a gripping member adapted to engage a rail flange and provided with a depending foot adapted to abut against the rear vertical face of a tie, a transverse connecting member adapted to underlie the rail base, and a locking member threaded on the end of the connecting member and adapted to be turned thereon to position to contact the opposite rail flange and provided with an upstanding portion adapted to be struck down onto the rail flange, substantially as described. 110

5. In a rail anchor, the combination of a gripping member provided with a jaw adapted to engage a rail flange, the jaw being provided with inner and outer flanges 115

and a connecting body portion, the inner flange being projected downwardly and inwardly to afford a foot having a bearing surface, and a rear reinforcing web interposed between the rear flange and the front flange with its depending foot, a transverse connecting arm adapted to extend below the rail base, and a locking member adjustable upon the arm and adapted to engage 10 the opposite rail flange, substantially as described.

6. In a rail anchor, the combination of a gripping member provided with a jaw adapted to engage a rail flange, the jaw being provided with inner and outer flanges and a connecting body portion, the inner flange being projected downwardly and inwardly to afford a foot having a bearing surface, and a rear reinforcing web interposed between the rear flange and the front flange with its depending foot, a transverse connecting arm adapted to extend below the rail base, and a locking member adjustable upon the connecting arm and provided with 25 an upstanding portion adapted to be struck down to overlie and engage the opposite rail flange, substantially as described.

7. In a rail anchor, the combination of a gripping member provided with a jaw 30 adapted to engage a rail flange, the jaw being provided with inner and outer flanges and a connecting body portion, the inner flange being projected downwardly and inwardly to afford a foot having a bearing 35 surface, and a rear reinforcing web interposed between the rear flange and the front flange with its depending foot, a transverse connecting arm adapted to extend below the rail base, and a locking nut threaded on the 40 end of the connecting arm and provided with an upstanding portion adapted to be struck down to overlie and engage the opposite rail flange, substantially as described.

8. In a rail anchor, the combination of a gripping member provided with a jaw 45 adapted to engage a rail flange, the jaw being provided with inner and outer flanges and a connecting body portion, the inner flange being projected downwardly and inwardly to afford a foot having a curved bearing surface, and a rear reinforcing web interposed between the rear flange and the front flange with its depending foot, a transverse connecting arm adapted to extend below the rail base, and a locking member adjustable upon the arm and adapted to engage 50 the opposite rail flange, the connecting arm being provided with a bend or curve therein to afford flexibility, substantially as described.

9. In a rail anchor, the combination of a gripping member provided with a jaw adapted to engage a rail flange, the jaw being provided with inner and outer flanges 65 and a connecting body portion, the inner

flange being projected downwardly and inwardly to afford a foot having a bearing surface, and a rear reinforcing web interposed between the rear flange and the front flange with its depending foot, a transverse connecting arm adapted to extend below the rail base, and a locking member adjustable upon the connecting arm and provided with an upstanding portion adapted to be struck down to overlie and engage the opposite rail flange, the connecting arm being provided with a bend or curve therein to afford flexibility, substantially as described.

10. In a rail anchor, the combination of a gripping member provided with a jaw 80 adapted to engage a rail flange, the jaw being provided with inner and outer flanges and a connecting body portion, the inner flange being projected downwardly and inwardly to afford a foot having a curved bearing surface, and a rear reinforcing web interposed between the rear flange and the front flange with its depending foot, a transverse connecting arm adapted to extend below the rail base, and a locking nut 85 threaded on the end of the connecting arm and provided with an upstanding portion adapted to be struck down to overlie and engage the opposite rail flange, the connecting arm being provided with a bend or curve therein to afford flexibility, substantially as described.

11. In a rail anchor, the combination of a gripping member adapted to engage a rail flange and provided with a depending foot adapted to abut against a tie, a connecting arm adapted to underlie the rail base and threaded at its outer end, a nut carried by the threaded end of the arm and provided with a collar having irregularities 100 formed thereon, adapting the collar to be turned to position to contact the opposite rail flange, and thereafter have a portion of the collar struck down to overlie and grip said flange and lock the nut in position, substantially as described.

12. In a rail anchor, the combination of a gripping member adapted to engage a rail flange, a connecting arm adapted to underlie the rail base and threaded at its 115 outer end, a nut carried on the threaded end of the arm and provided with a collar having notches formed therein and adapted to be turned up to abut against the opposite rail flange and have the collar struck 120 down to overlie and grip said flange and lock the nut in position, substantially as described.

13. In a rail anchor, the combination of a gripping member adapted to engage a rail flange and provided with a depending foot adapted to abut against a tie, a connecting arm adapted to underlie the rail base and threaded at its outer end, a nut carried by the threaded end of the arm and provided 125

- with a collar having irregularities formed thereon, adapting the collar to be turned to position to contact the opposite rail flange, and thereafter have a portion of the collar struck down to overlie and grip said flange and lock the nut in position, the connecting arm being provided with a bend or curve to afford flexibility, substantially as described.
- 10 14. In a rail anchor, the combination of a gripping member adapted to engage a rail flange, a connecting arm adapted to underlie the rail base and threaded at its outer end, a nut carried on the threaded end 15 of the arm and provided with a collar having notches formed thereon and adapted to be turned up to abut against the opposite rail flange and have the collar struck down to overlie and grip said flange and lock the 20 nut in position, the connecting arm being provided with a bend or curve to afford flexibility, substantially as described.
- 15 16. In a rail anchor, the combination of a gripping member having a jaw designed 25 to grip a rail flange, and a foot underlying the jaw and adapted to bear against the face of a tie, a cross-connecting arm adapted to extend below the rail base, and having 30 its horizontal dimension less than its vertical dimension, and provided with threads at its outer end on its upper and lower edges, a nut threaded onto the threaded end of the connecting arm and provided with a collar adapted to be turned 35 up to abut against the edge of the opposite flange and adapted to be struck down to overlie and grip the flange and lock the nut in position, substantially as described.
- 40 17. In a rail anchor, the combination of a gripping member having a jaw designed to grip a rail flange, and a foot underlying the jaw and adapted to bear against the face of a tie, a cross-connecting arm adapted to extend below the rail base, and having 45 its horizontal dimension less than its vertical dimension, and provided with threads at its outer end on its upper and lower edges, a nut threaded onto the threaded end of the connecting arm and provided with a 50 collar adapted to be turned up to abut against the edge of the opposite flange and adapted to be struck down to overlie and grip the flange and lock the nut in position, the connecting arm being bent or 55 curved to afford flexibility, substantially as described.
17. In a rail anchor, the combination of a jaw member adapted to grip the rail flange, a connecting arm adapted to extend under and in parallelism with the under 60 surface of the rail base and of a length to project beyond the rail base, and a locking member adjustable upon the projected end of the arm and provided with an upstanding member adapted, when the locking member is adjusted, to be struck down to grip the rail, substantially as described.
18. In a rail anchor, the combination of a jaw member adapted to grip the rail flange, a connecting arm adapted to extend 70 under and in parallelism with the under surface of the rail base and of a length to project beyond the rail base, and a nut threaded onto the projected end of the arm and provided at its inner side with a collar 75 adapted to be turned up to contact the opposite flange of the rail and to be thereafter struck down to overlie and grip said rail flange and to lock the nut in position, substantially as described.
19. In a rail anchor, the combination of a jaw member adapted to grip the rail flange, a connecting arm adapted to extend under and in parallelism with the under 80 surface of the rail base and of a length to project beyond the rail base, and a locking member adjustable upon the projected end of the arm and provided with an upstanding member adapted, when the locking member is adjusted, to be struck down to grip the rail, the connecting arm being provided with a bend or curve to increase its 85 flexibility, substantially as described.
20. In a rail anchor, the combination of a jaw member adapted to grip the rail flange, a connecting arm adapted to extend under and in parallelism with the under 90 surface of the rail base and of a length to project beyond the rail base, and a nut threaded onto the projected end of the arm and provided at its inner side with a collar 95 adapted to be turned up to contact the opposite flange of the rail and to be thereafter struck down to overlie and grip said rail flange and to lock the nut in position, the 100 connecting arm being provided with a bend or curve to increase its flexibility, substantially as described.
